US0D1024283S

(12) **United States Design Patent** (10) Patent No.: **US D1,024,283 S**
(45) Date of Patent: ** Apr. 23, 2024

(54) **DRAIN PROTECTOR**

(71) Applicant: **Helen of Troy Limited**, St. Michael (BB)

(72) Inventors: **Lance E. Hazelton**, Maplewood, NJ (US); **Mathieu Zastawny**, Jersey City, NJ (US); **Yoon Jung Heo**, Fort Lee, NJ (US)

(73) Assignee: **Helen of Troy Limited**, St. Michael (BB)

(**) Term: **15 Years**

(21) Appl. No.: **29/817,102**

(22) Filed: **Nov. 29, 2021**

(51) LOC (14) Cl. **23-01**

(52) U.S. Cl.

USPC **D23/261**

(58) **Field of Classification Search**

(57) **CLAIM**

The ornamental design for a drain protector, as shown and described.

DESCRIPTION

FIG. 1 is a perspective view of a drain protector showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The broken lines in the drawings depict portions of the drain protector that form no part of the claimed design.

1 Claim, 5 Drawing Sheets
